BONDED KNIFE HEAD AND KNIFE ASSEMBLY FOR RECIPROCATING MOWERS

Raymond J. Miller, Detroit, Mich., assignor to Ford Motor Company, Dearborn, Mich., a corporation of Delaware

Application November 16, 1953, Serial No. 392,289

2 Claims. (Cl. 56—306)

This invention relates to an improved knife construction

for agricultural mowers of the reciprocating knife type. For many years, substantially the same knife construction has been utilized in all commercially successful agricultural mowers, namely, the individual knife elements and the so-called knife head, by which the knife was connected to the driving pitman, were secured to an elongated backing strip by the utilization of one or more rivets or similar types of mechanical fasteners. However, it has been long recognized that this type of fastening left much to be desired in that shearing or other failure of the rivets during operation of the mower has been a continuous problem, resulting in relatively limited service life for any particular knife assembly before one or more rivets would have to be replaced.

Accordingly, it is an object of this invention to provide an improved knife assembly for reciprocated knife type mowers characterized by the utilization of both rivets and a layer of shock absorbing flexible bonding material to effect the securement of the knife sections and the knife head to the backing strip.

The specific nature of this invention, as well as other objects and advantages thereof, will become apparent to those skilled in the art from the following detailed description taken in conjunction with the attached drawings on which, by way of preferred example only, is illustrated one embodiment of this invention:

On the drawings:

Figure 1 is a partial perspective view of a knife construction embodying this invention;

Figure 2 is an enlarged scale plan view of the knife of Figure 1;

Fig. 3 is a sectional view taken on the plane 3—3 of Figure 2;

Figure 4 is a sectional view taken on the plane 4—4 of Figure 2; and

Figure 5 is a multi-plane sectional view taken on the line 5—5 of Figure 2.

As shown on drawings:

A knife construction embodying this invention utilizes conventionally shaped elements to form the knife assembly but provides a novel means for effecting the securement of such elements in assembly. Thus, a conventional backing strip 10 of the usual elongated configuration is provided, having a plurality of spaced apertures 10a there-

2

in for the reception of rivets 11 which mount conventional knife sections 12 and a knife head 13 to the backing strip 10 in conventional fashion. However, in accordance with this invention, additional securing means for both the knife sections 12 and the knife head 13 is provided in the form of a thin layer of shock absorbing flexible bonding material 14 which is interposed between the abutting surfaces of the backing strip 10, the knife sections 12, and the knife head 13.

The bonding material is preferably fabricated from a class of synthetic resin adhesives known as ethoxylenes¹. These compounds are obtained by etherification of dihydroxy compounds or diphenols with epichlorohydrin. A postulated chemical structure for this class of resins is indicated below:

These adhesives are suitably catalyzed for curing by the addition thereto of urea-formaldehyde, melamine-formaldehyde and phenol-formaldehyde resins. Other curing agents include polyamides and amines such as triethylamine, diethylene triamine and benzylidimethylamine.

Other metal to metal adhesives of the synthetic resin type are also applicable to use in the present invention and include the butadiene-acrylonitrile copolymer modified phenolics, related synthetic resin-rubber-type adhesives, and the like.

When using the resins disclosed, in accordance with the present invention, the knife head 13 is preferably assembled to the backing strip 10 under heat and pressure. First the surfaces of the parts to be joined are cleaned and coated with the catalyzed resin and clamped in an assembled relationship for curing. Curing may be effected at a temperature in the range from room temperature to 250° C., preferably in a range from about 90° to 150° C., for a period of time from about 0.25 to 2 hours. A temperature of about 100° C. was employed for curing the knife heads used in the tests hereinafter described at a cure time of about 1 hour.

With the aforescribed construction it has been found that greatly improved service life can be obtained from the knife assembly. For example, a knife assembly which was secured only by rivets was found by accelerated field test to have a service life of only 4.7 hours before one or more rivets failed, resulting in the disassembly of the knife head. It is even more interesting to note that tests of knife assemblies wherein the aforescribed elements were secured together only by the shock absorbing flexible bonding material 14 had a much shorter service life, averaging only 0.5 hour. However, with the combined rivet and shock absorbing flexible bonded construction embodying this invention, the average service life of the assembly before one or more elements thereof became disconnected averaged 63.3 hours, or an increase of approximately 1300% over the performance of the conventional riveted construction.

This unusual increase in service life can be theoretically explained as follows:

When rivets alone are used as a securing means, at

¹ "Natural and Synthetic High Polymers," 2nd ed., K. H. Meyer, 1950, Interscience Publishers, Inc., N. Y., pp. 258-259.

each stroke of the reciprocating knife assembly each knife section rivet is subjected to a large radial impact force with each reversal of movement of the knife assembly. Additionally, those rivets which secure the knife head to the assemblage were subjected to an axial component of impact force due to the fact that the pitman attached to such knife head inherently tends to alternately raise and depress the knife head relative to the backing strip. Also, the knife sections were subjected to continuous longitudinal flexing of the backing strip 10 as it was dragged over the ground or elevated to clear obstructions. Thus it was only a question of time until one or more rivets failed under the fatigue stress induced by such repeated impact forces. At the same time, however, the rivets were sufficiently rigid to adequately resist any substantial vertical displacement of the elements of the assembly relative to each other due to the flexing of the backing strip 10. On the other hand, when the shock absorbing flexible bonding material 14 is used alone, the impact forces due to the reciprocations of the assembly will be absorbed over the entire area of the bonded surfaces and hence are greatly reduced in intensity. However, such bonding material could not successively resist the relative displacements of the elements of assembly produced by flexing of the backing strip and thus would fail rapidly.

With the combination of rigid rivet-type fastenings and the shock absorbing flexible bonding material, the impact loading on the rivets was greatly reduced, hence increasing their service life and the vertical displacements of knife sections and knife heads relative to the backing strip due to flexing action were successfully opposed by the rigid rivets, hence minimizing the deterioration of the bonding material 14 with the over all result as indicated above, of a disproportionate but most desirable increase in service life of the new assembly.

It will, of course, be understood that various details of construction may be varied through a wide range without departing from the principles of this invention and it is,

therefore, not the purpose to limit the patent granted here-on otherwise than necessitated by the scope of the appended claims.

I claim:

5 1. In a reciprocating knife-type mower, comprising in combination a knife assemblage comprising a backing strip, a plurality of cutting elements mountable along said strip, rigid fastener means traversing said backing strip and said knife head for mechanically securing said knife head on said backing strip, and a layer of shock absorbing and flexible ethoxylene synthetic resin interposed between said head and said backing strip to adhesively unite said knife head and said backing strip and provide a shock absorbing flexible bond to said knife assemblage upon longitudinal flexing and radial loading.

10 2. In a reciprocating knife-type mower, comprising in combination a knife assembly subjected to longitudinal flexing and impact loading comprising a backing strip, a plurality of cutting elements mountable along said backing strip, a knife head mountable on one end of said backing strip, rigid fastener means respectively traversing said backing strip and said cutting elements and said knife head for mechanically securing said cutting elements and said knife head to said strip, and a layer of phenolic resin modified with a synthetic elastomer interposed between said cutting elements and said backing strip, and said knife head and said backing strip to adhesively unite said cutting elements and said knife head with said backing strip with a shock absorbing flexible bond.
